TIME DELAY FEATURE FOR FLAME FAILURE PROTECTIVE DEVICE

Filed Sept. 4, 1943

FIG. - 3

Carl M. Lathrop Inventor
By J. P. Young Attorney

UNITED STATES PATENT OFFICE

2,429,131

TIME DELAY FEATURE FOR FLAME FAILURE
PROTECTIVE DEVICECarl M. Lathrop, Elizabeth, N. J., assignor to
Standard Oil Development Company, a corpora-
tion of Delaware

Application September 4, 1943, Serial No. 501,330

3 Claims. (Cl. 158—28)

1

This invention relates to a flame-control safety device and in particular to a device having a variable time safety adjustment.

In many industries it is necessary to maintain flame combustion of fuels as a source of heat. As a necessary adjunct of such combustion, the fuel supply to the burner may be controlled in the event of flame failure in order to prevent explosions and similar hazards. Normally, a flame-failure protective device is employed. Such a device utilizes electric circuits to maintain the fuel valve open when the electrical resistance of the flame is within suitably established values and closed when the resistance of the flame is abnormally low or high or the flame itself is absent. In a particular instrument the distinction between flames of higher than normal conductivity and the total absence of a flame is very difficult to make practically. An industrially acceptable approach in an instrument is the lengthening of the time period between the detection of an unusually high conductivity and the closing of the fuel valve for safety purposes.

The present invention relates to an improved flame protective device. In this device a definite and easily adjustable time delay has been added between the occurrence of a momentary flame condition which would have unnecessarily closed the fuel valve in prior art equipment and the necessary closing of the fuel valve for safety purposes. The present flame control devices operate to sense the presence or supposed absence of flames at the burner equipment. The control of the fuel supply to burners is dependent upon the electrical conductivity of the flame. Though industrially advantageous in many applications, the prior art devices are deficient in failing to distinguish between flames of higher than general conductivity and the total absence of a flame.

An object of the invention is to furnish a device in which by a simple means a lengthening of the time period can be made and the period of time delay suitably adjusted. Another object of the invention is to furnish a control apparatus for fuel burners in order to avoid explosions and similar hazards which could arise if the burner admits fuel when no flame is present. Another object of the invention is to furnish devices having delayed action features which are consistent with safety and reliability of operation.

In Figure 1 the variation in conductivity with time for a typical flame condition at a burner is presented and also the areas indicated in which the switch in the main circuit controlling the fuel valve of prior art protective devices operates to

2

cut off the fuel supply. In Figure 2 a circuit is shown presenting an embodiment of the present invention. Fig. 3 is a diagram showing selective connections for a time delay condenser.

In the past flame protective devices have not been satisfactory, particularly in regard to certain momentary fluctuations in the flame resistance which cause the immediate closing of the fuel valve in prior art equipment when there had been no actual flame failure, but merely a change in the electrical resistance of the flame. Thus, the introduction of the time delay period consistent with safety and reliability of operation as made convenient in the device of this invention would seem necessary. This is particularly evident with auxiliary burner equipment connected to petroleum cracking units. This auxiliary equipment operates to supply heated gases for bringing the main equipment up to starting temperatures prior to operation. In this latter utilization, present devices have a delay period of the order of .5 second when the resistance exceeds an upper limit and about 0.001 of a second delay period when the resistance falls below a certain lower limit. While the period can be adjusted at the upper limit, that at the lower limit is determined solely by the frequency characteristics of the available power supply. The practically instantaneous action of the prior art devices at the lower resistance limit has caused many false or unnecessary closings of the fuel supply valve. Such defects are eliminated by the improved devices of this invention.

It is generally recognized that, according to the quality of the flame, the flame resistance varies between approximately 10 megohms and about 0.4 megohm without the flame being extinguished. However, the combustion of many mixtures, especially the hydrocarbon mixtures which give orange tracers in combustion, give rise to flames of resistance of about 0.4 megohm. A satisfactory time delay device, therefore, should function at the lower resistance after such a time delay period as is consistent with safety and reliability of operation and should have a recovery time sufficiently short to prevent integration over a number of short periods of low flame resistance that would result ultimately in the closing of the fuel valve. The device of the present invention has such advantageous features.

In the embodiment of the invention shown in Figure 2 a customary flame protective device is arranged to actuate switch 10. The switch 10 is maintained closed by the flame protective device during normal operation of the flame in

the fuel burner, thereby energizing relay 12 and keeping contact 14 closed. With contact 14 of relay 12 closed solenoid 16 is energized from terminals 18 sufficiently to hold the fuel valve 20 open and the condenser 22 is charged to a potential V. Terminals 28 supply direct current or pulsating direct current power through the flame protective device. The terminals 18 may represent an external source of either direct or pulsating direct current.

Upon the actual failure of the flame or supposed failure as sensed by the flame protective device, switch 10 is opened and current no longer flows from the terminals through relay 12 and resistor 24. However, upon the opening of the switch 10 the charge then held on the condenser 22 flows through the solenoid of the relay 12 and the resistor 24. The condenser 22 is of sufficient capacity to maintain adequate current through relay 12 as to maintain contact 14 closed, thereby preventing the valve 20 from operating until such time as the condenser 22 shall have discharged itself to a point that the potential difference then available between the terminals 28 and 30 is insufficient for relay 12 to maintain contact 14 closed, at which time the solenoid 16 is deenergized and the valve 20 is closed.

If switch 10 should momentarily open and then close before the potential difference between terminals 28 and 30 becomes too low (as described above) for relay 12 to maintain contact 14 closed, valve 20 will not close but will continue to remain open.

Determination of the size of the condenser 22, resistor 24 and the resistance of relay 12, as well as the value of potential difference between terminals 28 and 30 for relay 12 to allow contact 14 to open will depend upon the amount of the time delay desired and, therefore, no fixed value is claimed, this being the predeterminable time delay.

In the device of this invention, minor changes in the time delay may be made by adjusting the tension of the relay spring 32 by means of the adjusting screw 34. In order to increase the time delay, the spring tension may be reduced, while to decrease the time delay, the spring may be put under greater tension. Major adjustments

in the time delay period may be made by changing the wiring of the condenser 22 according to the manner presented in Figure 3, in which various combinations of three condensers are shown.

8 The invention now having been described and illustrated, what is claimed is:

1. In a delayed action flame protective device the combination which comprises a flame responsive device sensitive to the varying conductivity of a flame, an electric circuit, an electric switch in such circuit operated by said flame responsive device, an electromagnetic relay and a resistor connected in series in said circuit, condenser means of predetermined capacity for storing electric energy connected in parallel with said relay and resistor, a second electric circuit, a fuel valve operated by said second circuit, and an electric switch in said second circuit operated by said electromagnetic relay.
- 10 2. A delayed action flame protective device according to claim 1 in which said electromagnetic relay comprises an adjustable spring for biasing the last-named switch to open position.
- 15 3. A delayed action flame protective device according to claim 1 in which said condenser means comprises combinations of individual condensers of small capacity, and selective connections between said condensers for prolonging or reducing the period of the delayed action.
- 20 4. A delayed action flame protective device according to claim 1 in which said condenser means comprises combinations of individual condensers of small capacity, and selective connections between said condensers for prolonging or reducing the period of the delayed action.
- 25 5. A delayed action flame protective device according to claim 1 in which said condenser means comprises combinations of individual condensers of small capacity, and selective connections between said condensers for prolonging or reducing the period of the delayed action.

30 CARL M. LATHROP.
